UNITED STATES PATENT OFFICE

119,370

DESIGN FOR A GAME BOARD

Willard E. Andrews, Sycamore, Ill.

Application November 15, 1939, Serial No. 88,299

Term of patent 7 years

To all whom it may concern:

Be it known that I, Willard E. Andrews, a citizen of the United States, residing at Sycamore, in the county of De Kalb and State of Illinois, have invented a new, original, and ornamental Design for Game Boards, of which the following is a specification, reference being had to the accompanying drawing, forming part thereof.

I claim:
The ornamental design for a game board, as shown.

WILLARD E. ANDREWS.
